INJECTOR

James B. Hopper, Lodi, Calif.

Application June 6, 1944, Serial No. 538,952

5 Claims. (Cl. 122—456)

The present invention relates to improvements in an injector for automatically replenishing the water supply of a boiler with preheated feed water at regular intervals, when requisite, wherein auxiliary and reserve tanks connected thereto operate in conjunction with control valves actuated by the lowering and raising of the water level within said boiler to automatically provide the required replenishment to maintain a substantially constant water level at a substantially constant temperature and a substantially constant production of steam.

The primary object of the present invention, then, is to provide a new and improved injector of the character set forth having improved means for automatically maintaining a substantially constant water level within a steam boiler.

Another object is to provide a new and improved injector having a greatly simplified construction, economy of operation, and a maximum efficiency.

A further object is to provide a new and improved injector of the type described having improved means for preheating and holding in reserve a supply of water for injection into said boiler when required.

I accomplish these and other objects by means of the improved device disclosed in the drawing forming a part of the present application, and in which—

Fig. 1 is a vertical sectional view, partly schematic, of a steam boiler with my improved injector connected thereto; and

Fig. 2 is an enlarged vertical sectional view of the auxiliary tank and valve control connected thereto.

Referring to the drawing:

The numeral 1 is used to designate in general a steam boiler provided with a suitable burner 2 and vertically disposed pipes 3 for conveying the products of combustion through said boiler 1 and the usual water therein to a suitable stack 4. An auxiliary tank 6 adjacent said boiler 1 has a drain 7 connecting the bottom thereof to the lower portion of the boiler 1, while a steam bypass 8 connects the upper portion of said boiler 1 with the upper portion of the auxiliary tank 6, the purpose of which will hereinafter be more fully set forth.

A two-way trip-valve 9 is mounted upon the tank 6 and connected thereto, and encloses upper and lower valves 10 and 11, respectively, mounted upon a common valve stem 12 and operate to alternately engage their respective valve seats 10' and 11'. The stem 12 preferably is operatively

connected to and operated by the arm 30 of a ball float 14 pivotally mounted within the auxiliary tank 6 and between upper and lower springs 31 and 32, respectively, mounted upon the lower end of the said stem 12 which extends downwardly through the two-way trip-valve 9 and into said tank 6. The upper seat 10' of the valve 9 is provided with vents 15 leading to the atmosphere.

A reserve tank 16 is mounted upon one end of the tank 6 and has a float valve 17 caged in the upper part thereof to control entrance to a chamber 18 on top of said reserve 16 from which chamber 18 a pipe 19 or other suitable connection leads to the valve 9 at a point midway between the seats 10' and 11' of the valve 9. A by-pass 20 leads from the pipe 19 to a point in said valve 9 above the upper valve seat 10' and valve 10 thereof.

A water supply pipe 21, leading from a water source, not shown, is provided with a constant pressure regulating valve 22, to control the pressure of said water supply to said tank 6, and a steam pressure regulating valve 23 and a check valve 24 to prevent a return flow of water from said tank 6 to said supply. Beyond the check valve 24 the water pipe 21 divides into a Y, the upper branch of which is freely connected to the lower portion of the reserve tank 16 while the opposite branch of said Y is connected to the tank 6 and is provided with a check valve 26 to permit water to flow into said tank 6 from said pipe 21 or tank 16, but to prevent a return flow of water from said tank 6.

In operation:

Normally, the level and temperature of the water and steam in the boiler 1 and auxiliary tank 6 are maintained substantially equal by means of the connections 7 and 8. The steam pressure and heat thereof, then, in addition to preheating the water in the reserve 16, also presses the valve 11 against its seat 11', when the ball float 14 is up, until the water level drops said ball float 14 to a point where the arm 30 compresses, by means of increased leverage, the lower spring 32 upon the stem 12 until the tension of said spring 32 is sufficient to unseat the valve 11 and to seat the valve 10 upon its vented seat 10', thereby closing the connection or pipe 19 to the atmosphere.

The valve 11 being open, steam passes from the tank 6, through pipe 19 into the chamber 18 and against the enlarged and flat valve 17. As the steam pressure is greater than the normal water pressure from the pipe 21, the valve 17 is opened and the pressure exerted by the steam

on top of the water in the reserve 16 forces said water through the Y, check valve 26 and into the tank 6.

When the tank 6 is thus replenished, the rising water level therein raises the ball float 14 until its arm 30 compresses the upper spring 31 sufficiently to close the lower valve 11 and open the upper valve 10, thereby uncovering the vents 15 and opening the pipe 19, through the by-pass 20, and the upper part of the reserve 16 to the atmosphere, so that the normal pressure of the supply pipe 21 may refill the reserve 16 until the water level thereof engages the float valve 17 and closes the same against the opening of the chamber 18. As the top of the reserve tank 16 is thus closed, the flow of water thereinto will cease as soon as the air above it is compressed to a sufficient degree to resist further flow.

The pressure regulator indicated schematically at 22 is provided to prevent a sudden inrush of cold water into the tank 6 and boiler 1, in case the pressure and temperature of said boiler 1 should inadvertently or otherwise drop to a pressure below the normal pressure of the water supply. Similarly, in reverse, the steam pressure regulating valve indicated schematically at 23, is provided to prevent an excessive steam pressure from backing up and escaping into said water pipe 21.

By means of the foregoing, it is obvious that I have provided a greatly simplified, economically operated and efficient automatic injector for automatically maintaining a substantially constant water level within a boiler and replenishing the same with a supply of automatically preheated feed water so that no excessive variations and loss of power or steam is permitted, thus preventing a loss of time and the use of the boiler.

Having described my invention, I claim:

1. An injector comprising the combination with a boiler of an auxiliary tank; connections from the top and bottom of said boiler to the top and bottom of said auxiliary tank; a reserve tank mounted upon and in contact with said auxiliary tank; a connection from the top of said auxiliary to the top of said reserve; valve means interposed in said last connection and normally actuated by a water level within said boiler and auxiliary tank to permit the passage of steam from said auxiliary into the top of said reserve to force water therein into said auxiliary tank; a connection from the bottom of said reserve to said auxiliary tank; and a ball float caged within the upper portion of said reserve and actuated by a rising water level therein to close the connection from the top of said reserve to said auxiliary.

2. An injector comprising the combination with a boiler of an auxiliary tank; connections from the top and bottom of said boiler to the top and bottom of said auxiliary tank; a reserve tank mounted upon and in contact with said auxiliary tank; a connection from the top of said auxiliary to the top of said reserve; valve means interposed in said last connection and normally actuated by a water level within said boiler and auxiliary tank to permit a passage of steam from said auxiliary to said reserve; a connection from the bottom of said reserve to said auxiliary tank; a ball float caged within the upper end of said reserve and actuated by a rising water level within said reserve to close the connection from the top thereof to the top of said auxiliary; a connection from the bottom of said reserve to said auxiliary; a check valve mounted in said connec-

tion between the bottom of the reserve and said auxiliary and arranged to permit passage from said reserve into said auxiliary only; a water supply pipe connected to said connection at a point above the check valve therein; and means in said water supply pipe to prevent a return flow of water therethrough.

3. An injector comprising the combination with a boiler of an auxiliary tank adjacent thereto; a drain connecting the lower portion of said auxiliary with the lower portion of said boiler; a steam by-pass connecting the upper portion of said boiler with the upper portion of said auxiliary; a reserve tank mounted upon and in contact with one end of said auxiliary; a two-way trip-valve mounted upon and connected to said auxiliary and provided with vents; a connection from said valve to the upper end of said reserve; valve means mounted within said two-way trip-valve and extending into said auxiliary and actuated by a falling water level within said auxiliary to connect the same with the upper portion of said reserve and actuated by a rising water level to connect said reserve with said vents; and a ball float pivotally mounted within said auxiliary and operatively connected to said trip-valve to operate the same.

4. An injector comprising the combination with a boiler of an auxiliary tank adjacent thereto; a drain connecting the lower portion of said auxiliary with the lower portion of said boiler; a steam by-pass connecting the upper portion of said boiler with the upper portion of said auxiliary; a reserve tank mounted upon and in contact with said auxiliary; a two-way trip-valve mounted upon and connected to said auxiliary and provided with vents; a connection from said valve to the upper end of said reserve; valve means mounted within said two-way trip-valve and extending into said auxiliary; and a ball float pivotally mounted within said auxiliary and operatively connected to said valve and actuated by a falling water level to open said valve and said auxiliary to said reserve and to close said vents, and actuated by a rising water level to close said auxiliary to said reserve and to open said reserve to said vents; and a connection from the bottom of said reserve to said auxiliary.

5. An injector comprising the combination with a boiler of an auxiliary tank adjacent thereto; a drain connecting the lower portion of said auxiliary with the lower portion of said boiler; a steam by-pass connecting the upper portion of said boiler with the upper portion of said auxiliary; a reserve tank mounted upon and in contact with said auxiliary; a two-way trip-valve mounted upon and connected to said auxiliary and provided with vents; a connection from said valve to the upper end of said reserve; valve means mounted within said two-way trip-valve and extending into said auxiliary; a water connection between the bottom of said reserve and said auxiliary; a check valve in said connection to permit a flow from said reserve to said auxiliary only; a ball float pivotally mounted within said auxiliary and operatively connected to said valve and actuated by a falling water level to open said valve and auxiliary to the top of said reserve and to close said vents, and actuated by a rising water level to close said auxiliary to said reserve and to open said reserve to said vents; a caged float valve within said reserve to close the same to said vents when said reserve is filled.
